[57] CLAIM

The ornamental design for a combined picnic table and bench, or similar article.

DESCRIPTION

FIG. 1 is a front perspective view of a combined picnic table and bench, showing my new design with the table component in one operative position;

FIG. 2 is a top plan view thereof;

FIG. 3 is a front elevational view thereof;

FIG. 4 is a rear elevational view thereof;

FIG. 5 is an end elevational view thereof;

FIG. 6 is an end elevational view, showing the table component adjusted to vertical backrest position;

FIG. 7 is a front perspective view, showing the table component in the FIG. 6 position; and

FIG. 8 is an end elevational view, showing the table component adjusted to inclined backrest position.
